UNITED STATES PATENT OFFICE.

MOSES S. BEACH, OF BROOKLYN, NEW YORK.

APPARATUS FOR WETTING PAPER.

Specification of Letters Patent No. 22,009, dated November 9, 1858.

To all whom it may concern:

Be it known that I, MOSES S. BEACH, of the city of Brooklyn, in the county of Kings and State of New York, have invented a new and valuable Improvement in Wetting Paper; and I do hereby declare that the following is a full and exact description thereof, reference being had to the accompanying drawings and to the letters of reference 10 marked thereon.

To enable others skilled in the art to make and use my invention I will proceed to describe its construction and operation.

The object of my invention is to wet paper in rolls or endless sheets for use in printing presses in which the paper is supplied from such rolls or endless sheets.

The accompanying drawings represent one of the methods of applying it. 20 Figure 1 is a sectional view of a wetting machine at the red line *a, b*, in Fig. 2, and Fig. 2 is a vertical view of the machine.

A is a roller around which the dry paper (indicated by red lines) is first placed. 25 *B* is a small roller over which the paper passes and upon which it is wet on its way to the roller *C* upon which it is wound after being wet.

D is a tank of water having a projecting lip or table *d* on one side.

E is a piece of flannel, (represented by blue lines) a part of which is immersed in the tank *D*, and the rest spread over the lip *d* of the tank *D* and upon the paper on roller *B*. Motion is given to the machine 35 by a crank or pulley attached to roller *C*.

The operation of the machine consists simply in winding the paper off from roller *A* upon the roller *C* the water passing by capillary attraction, through the flannel and 40 depositing itself upon the paper, while it is passing the roller *B*. The quantity of water is regulated by elevating or depressing the lip attached to the tank *D*. Other kinds of cloth may be used to effect the same purpose but I find flannel best adapted. The flannel may also rest upon a roller instead of upon the paper and the roller communicate the water to the paper, but I prefer the 45 direct method shown in the drawings. 50

What I claim as my invention and desire to secure by Letters Patent is—

The employment of the cloth arranged and operating substantially as and for the purposes described.

M. S. BEACH.
